UNITED STATES PATENT OFFICE.

FRANZ X. ZIRNKILTON, OF PHILADELPHIA, PENNSYLVANIA.

NECKLACE-CLASP.

1,081,184.

Specification of Letters Patent.

Patented Dec. 9, 1913.

Application filed May 28, 1913. Serial No. 770,424.

To all whom it may concern:

Be it known that I, FRANZ X. ZIRNKILTON, a citizen of the United States, residing in Philadelphia, Pennsylvania, have invented 5 certain Improvements in Necklace-Clasps, of which the following is a specification.

One object of my invention is to provide a novel and relatively simple device for detachably connecting the ends of a necklace 10 or for separably coupling any two pieces or parts of jewelry, the construction being such as to permit of the quick and convenient connection or separation of such parts, while preventing their accidental uncoupling or 15 disconnection.

A further object of my invention is to provide a necklace clasp or similar device having the above noted characteristics, which at the same time, shall be of such a 20 nature as to add rather than detract from the ornamental appearance of the necklace or other article of jewelry with which it is used.

These objects and other advantageous 25 ends I secure as hereinafter set forth, reference being had to the accompanying drawings, in which:—

Figure 1 is a front elevation of a portion 30 of a necklace with a pendant, showing my invention as applied thereto; Fig. 2 is a rear elevation of the pendant shown in Fig. 1, further illustrating the invention and showing the clasp in its engaged position; Fig. 3 is a rear elevation similar to Fig. 2, showing 35 the clasp in its disengaged position; Fig. 4 is a side elevation of the pendant shown in Fig. 1; Figs. 5, 6, and 7 are side elevations of the pendant illustrating the steps necessary for the purpose of disengaging the clasp; and Fig. 8 is a plan of a 40 form of my invention in which two detachable clasps are employed.

In the above drawings, 1 and 2 represent 45 the two ends of a necklace which are illustrated as connected to the opposite ends of the pendant 3, the latter being provided at one end with a ring 4 to which the part 2 of the necklace is permanently secured. The end 1 of the necklace is likewise permanently secured to a ring 5 which in turn is soldered or otherwise connected to the middle portion of a substantially U-shaped clasp 6 made of spring metal having at its extremities two projections or pins 7 extending toward each other. 55

As is shown in Figs. 5 to 7 inclusive, the

pendant which in this case consists of a substantially elliptical open metal frame, has a groove 8 extending from one end to the middle of its two sides where it terminates in two inwardly extending cavities or recesses 9. From these cavities to the opposite end of the pendant, I preferably form the latter with a convex bead 10, so that when the clasp 6 lies within the groove 8, its appearance is substantially the same as that of said bead. 60 65

As shown in Fig. 7, the cavities or depressions 9 not only open on the sides of the pendant but are also open on the bottom 70 thereof, and the construction is such that there is a raised edge 11 between the groove 8 and the plane of the back of said pendant.

As before noted, the end 1 of the necklace is permanently attached to the ring 5 forming part of or connected to the U-shaped clasp 6, and when it is desired to attach the latter to the pendant, its projections 7 are entered in the groove 8 adjacent the end of said pendant as shown in Fig. 3. The clasp 80 is then pushed toward the pendant thus causing its ends to be gradually spread apart by the diverging walls of the groove 8 until the projections enter or snap into the recesses 9. The clasp 6 then lies within 85 the groove 8 as shown in Figs. 2 and 4, and so closely fits the same that it is practically indistinguishable from the bead 10 and its associated parts at the opposite end of the pendant. Owing to the springy nature of 90 the clasp, it cannot be accidentally dislodged from the groove and it is practically impossible to disengage its projections 7 from the recesses 9 by tension exerted on the ring 5.

When it is desired to detach the clasp 95 from the pendant, its ring-carrying end is forced in the direction of the arrow Fig. 4 so that it pivots on its projections 7 and finally comes into the position shown in Fig. 5. The recesses 9 are so made that at this 100 time the clasp cannot be removed by a straight away pull, but must be again swung on its projections 7 in the direction of the arrow Fig. 5, whereupon its end portions immediately adjacent said projections, fulcrum on 105 the adjacent parts of the rib or projecting edge 11 and cause its ends to be sprung apart, at the same time that the projections are moved laterally out of their recesses. The clasp occupies the position shown in 110 Fig. 7, immediately after its disengagement from the pendant.

While I have described my invention as applied to a necklace having a pendant, it obviously has many other uses, since it may without material change be applied to clasps 5 used in connection with lockets, watch fobs and many other forms of jewelry.

In the case shown in Fig. 8, I have shown a member 3^a, which may be a pendant or other article of jewelry of any desired form, 10 and two clasps 6^a designed to detachably engage its opposite ends. Obviously in this case the bead 10 would be omitted and the said member formed with a groove extending completely around it as shown.

15 I claim:—

1. The combination in a clasp of a member having grooves in opposite sides, each provided with a recess; a U-shaped piece of 20 spring material having projections adjacent its ends formed to enter the recesses; and means for causing the disengagement of said projections from the recesses when said U-shaped member is moved successively in opposite directions on said projections as pivots.

2. The combination in a clasp of a member having grooves in opposite sides provided with slots opening in lines substantially at right angles to the plane of said 30 grooves; with a U-shaped spring piece formed to fit the grooves and having projections removably entering the slots.

3. The combination in a clasp of a member having a groove formed in a portion of 35 two of its opposite sides, there being oppositely placed slots communicating with said groove and opening at right angles thereto; with a U-shaped spring piece having projections extending toward each other and 40 removably fitting the slots.

4. The combination in a clasp of a member having two cavities in its opposite sides; a U-shaped piece having projections removably fitting said cavities; and means for causing said projections to be forcibly removed from the cavities when said piece is successively moved in opposite directions on the projections as pivots.

5. The combination in a clasp of a member having a groove extending from the middle of two of its opposite sides to one end and a bead complementary to said groove, extending from the middle of said two sides to its opposite end, there being a cavity opening on the bottom face of said member 55 between the end of the groove and the end of the bead on each side thereof; with a U-shaped piece of spring material having projections at its ends extending toward each other and formed to removably fit into the 60 said cavities, said U-shaped piece being formed to fit within the groove.

6. The combination of a member having an encircling bead, a portion of which is formed by a removable substantially U- 65 shaped spring piece extending within a groove in the sides of said member, said piece having end portions seated in cavities in the body of said member and said cavities opening on one face of the member as 70 well as on the sides thereof so as to permit of the removal of said piece.

In testimony whereof, I have signed my name to this specification, in the presence of two subscribing witnesses.

FRANZ X. ZIRNKILTON.
